(57) **CLAIM**

The ornamental design for a d-ring, as shown and described.

DESCRIPTION

FIG. 1 shows a perspective view of my design for a d-ring;
FIG. 2 is a front view thereof;
FIG. 3 is a back view thereof;
FIG. 4 is a top view thereof;
FIG. 5 is a bottom view thereof;
FIG. 6 is a side view thereof; and,
FIG. 7 is another side view thereof.
The d-ring of the present invention is designed to attach to a
piece of webbing.
